CLAIM

The ornamental design for a rotary shaver, as shown and described.

DESCRIPTION

FIG. 1 is a right side elevational view of a rotary shaver showing my design therefor;
 FIG. 2 is a front elevational view thereof;
 FIG. 3 is a left side elevational view thereof;
 FIG. 4 is a rear elevational view thereof;
 FIG. 5 is a top, right, front perspective view thereof;
 FIG. 6 is a top plan view thereof;
 FIG. 7 is a top, left, front perspective view thereof;
 FIG. 8 is a top, right perspective view thereof;
 FIG. 9 is a bottom, left, front perspective view thereof;
 FIG. 10 is a bottom plan view thereof;
 FIG. 11 is a bottom, right perspective view thereof; and,
 FIG. 12 is a bottom, right, side perspective view thereof.
 The broken lines illustrate portions of the rotary shaver that form no part of the claimed design.
